UNITED STATES PATENT OFFICE

111,110

DESIGN FOR A COMBINATION ASHTRAY AND MATCH BOX HOLDER

Martin Secan, Highland Park, Mich.

Application March 16, 1938, Serial No. 75,869

Term of patent 7 years

To all whom it may concern:

Be it known that I, Martin Secan, a citizen of Yugoslavia, residing at Highland Park, in the county of Wayne and State of Michigan, United States of America, have invented a new, original, and ornamental Design for a Combination Ashtray and Match Box Holder, of which the following is a specification, reference being had to the accompanying drawing, forming a part thereof.

Figure 1 is a perspective view of a combination ashtray and match box holder showing my new design; and

Figure 2 is a side elevational view thereof.

The characteristic features of my design reside in an ashtray of substantially the contour shown, one side thereof being provided with a recessed enlargement arranged within the confines of the ashtray and extending above the upper edge of the rim of said ashtray, the inner wall of the enlarged portion being flat and extending perpendicular to the base of the ashtray.

I claim:

The ornamental design for a combination ashtray and match box holder, substantially as shown and described.

MARTIN SECAN.
